UNITED STATES PATENT OFFICE

JOHN E. SPENCER, OF SALEM, MASSACHUSETTS

LEATHER GRAINING, BOARDING, AND SOFTENING MACHINE

Application filed September 6, 1923. Serial No. 661,188.

This invention relates to machines for graining, boarding and softening leather of that type disclosed in my Patent No. 1,330,962 granted February 17, 1920. In this patent 5 the upper carrier is brought down toward the lower carrier for engagement of a skin therebetween by a treadle, the weight of the operator less the effective weight of a counterbalance which normally holds the upper 10 carrier raised being effective for that purpose.

In the machine of the present invention power mechanism for this action is employed. In order, however, to accommodate varying 15 thicknesses of leather, as well as to prevent serious injury to the operator should his hand become caught between the carriers, the upper carrier is permitted to come down by its own weight, which may be more or less 20 counterbalanced by a counterbalance weight.

In order to actuate the power mechanism in this manner a special clutch has been devised so that by depressing a treadle the upper carrier descends and there remains as 25 long as the treadle is held depressed, and on releasing the treadle the carrier rises. This clutch is of that type employing a pin carried by the driven member and projected by a spring into engagement with the driving 30 member when it is required to couple these members. This clutch is so designed that prevention of undesired projection of the pin is insured.

A further feature of the invention resides 35 in the driving mechanism, that for driving the carriers being entirely independent from that for raising the upper carrier and permitting it to descend.

A further feature relates to means for adjusting the bearing of the carrier on the work.

Further features relate to the mounting and the actuation of the antifriction plate between the carriers.

Further features and advantageous details and combinations of parts will appear from a more complete description of an embodiment of the invention illustrated in the accompanying drawings in which

Figure 1 is a perspective of the machine.

Figure 2 is a horizontal section just above the drive shaft substantially on line 2—2 of Figure 3.

Figure 3 is a vertical section on line 3—3 of Figure 2. 55

Figure 4 is a detail showing an adjustment. Figure 5 is an end view of a clutch.

Figure 6 is a section through the clutch-controlling yoke on line 6—6 of Figure 5. 60

Figure 7 is an end view of the driving member of the clutch.

Figure 8 is a similar view of the driven member.

Figures 9 and 10 are sectional details 65 through the clutch elements showing them in clutched and unclutched positions, respectively.

Referring to these drawings, the machine comprises upper and lower endless belt carriers 1 and 2, the lower carrier being preferably fixed in end frame members 3, while the upper member is rockable about the axis of the drive shaft 4 in the same manner as in the patent above mentioned. The lower carrier for the endless surface member or belt has a rear roller 5 over which the endless belt 6 passes and a forward roller 7. This forward roller is journaled in universally mounted bearings 8 each carried by a yoke 9. This yoke has a stem portion 10 which is longitudinally adjustable in a perforation 11^a in the corresponding end frame and it may be adjusted longitudinally in order to properly tension the belt or surface member 6 by means of a bolt 11 threaded through a transverse web 12 in the end frame and bearing against the inner rear end of the stem. The upper carrier or bolster member has an endless belt 15 supported over a forward roller 16 mounted in universally turnable bearings 17 adjustable longitudinally of end frames 18 in the same manner as the bearing 8. The rear roller 19 is fixed to the shaft 4 as in the patented machine. This upper bolster is partially counterbalanced so that the desired pressure may be obtained between the traveling surfaces of the carriers by the uncounterbalanced portion of its weight. A pair of 95 arms 20 may extend rearwardly from and in

55

line with the frame members 18 to receive the counterbalance weights.

In order that the upper carrier may adapt itself automatically to varying thicknesses of leather and also so that serious injury may not result in case the operator's arms or hands should accidentally become caught between the carriers, provision is made by which the upper carrier is raised by power from its operative position, but is permitted to descend by the action of its uncounterbalanced weight only, the power mechanism merely retracting and permitting the carrier to follow. The construction by which this is accomplished is as follows.

Referring more particularly to Figures 1 and 2, at 21 and 22 are shown two aligned shafts journaled at their adjacent ends in a bearing 23 fixed in a cross frame member 24 of the machine and at their outer ends in bearings 25 carried by the end frame members 3. The shaft 21 has fixed thereto a pinion 26 which meshes with a gear 27 rotatable on a shaft 28 and arranged to be clutched thereto when desired by a clutch, which will later be described. The shaft 28 has fixed thereto immediately within the end frames 3 the eccentrics 29, each having an eccentric strap 30 to which is fixed the lower end of a rod 31. The upper end of each rod is threaded and passes loosely through an eyebolt 32 swiveled on its shank 33 to one of the upper end frames 18 forwardly of the shaft 4. Each rod 31 has threaded thereon an abutment nut 34 on which the collar 32 may rest, this nut being fixed in adjusted position by means of a lock nut 35. When the eccentric strap is moved upwardly and the rod 31 correspondingly moved, the abutment nut 34 engaging the lower face of the collar 32 acts to push the upper carrier away from the lower carrier. This action takes place during one-half the revolution of the shaft 28. During the other half of the revolution of this shaft, the rods 31 are lowered, thus permitting each collar 32 to follow in contact with the nut 34 as the corresponding rod 31 descends.

There is also positioned between the carriers, as in the patent above mentioned, an anti-friction plate 40 which serves to separate the ingoing and outgoing portions of the skin during the operation of the machine. When the upper carrier is raised, it is desirable that this plate be raised also in order to permit the ready insertion of work. Means are provided in this invention for accomplishing this action by the power means which acts to raise the upper carrier and to permit it to lower. For this purpose the plate 40 has fixed thereto adjacent each end a yoke 41, each of which, as shown more particularly in Figure 3, is threaded at its lower central portion for the adjustable reception therethrough of a push rod 43 held in

adjusted position by means of a check nut 42. This rod 43 slides through a guide comprising an eyebolt 43' swiveled to the frame 3 and when pushed upwardly acts to raise the plate. A collar 43^a on the upper end of this rod furnishes a stop to limit the downward movement of the push rod by its impingement on the eyebolt 43'. The lower end of each rod 43 is pivoted at 44 to the forward end of a lever 45 which has its rear end fulcrumed on a pin 46 adjacent the rear edge of each end frame 3. Intermediate its ends each arm 45 is provided with the projecting surface portion 47 which at certain times rides on a roller 48 journaled on a pin 49 projecting from the upper end of one of the eccentric straps 30. With this construction, as the eccentric rotates, the lever 45 is swung upwardly by power when contacted by the roller 48 and is then allowed to swing downwardly, its upward swinging motion being timed with the upward motion of the rod 31 so that when the upper carrier is raised, the plate 40 is also raised, but to a less extent, and when the upper carrier is permitted to descend, the plate 40 is also permitted to descend until it rests upon the work supported on the lower carrier. The parts are so proportioned that the rods 43 descend to an extent sufficient to permit the plate 40 to rest on the work regardless of varying thicknesses thereof, sliding through the perforations of the eyebolt as far as permitted by the collar 43^a. In order to properly stiffen this plate 40, it is preferable to apply to its forward edge a stiffening bead 50. As this bead adds considerable weight to this portion of the plate it is likely to cause the eyebolt to cramp on the rods 43, thus preventing their free relative movement the weight of the work also causing the same tendency. For this reason the rear edge of the plate 40 may have means for counterbalancing the weight of the bead and the work such means, as shown, comprising a pair of springs 52, one adjacent each end frame of the machine, the lower end of each spring engaging a perforation 53 in an ear 54 extending upwardly from one of the levers 45, and its upper end engaging a rod 55 threaded at its upper end where it passes through the plate 40, an adjusting thumb nut 56 being applied to the upper end thereof to adjust the tension of the spring 52.

When the upper carrier is down in operative position the lower stretch 60 of its belt is in confronting relation to the upper stretch 61 of the lower carrier belt and in order that they may be held in proper relation to the work, transversely positioned bars 62 and 63 may be employed, these bars being adjustable substantially perpendicular to these stretches of the upper and lower belts and acting to determine their distance apart. If desired also these bars, which are arranged at intervals

throughout the length of each stretch may be bridged more or less by pressure plates such as 64. For the purpose of adjusting these bars as above mentioned, each bar may have its end face formed tapered, as shown for example in Figure 4 for the bar 62, at 70, and cooperating therewith is an endwise adjustable wedge member 71. This wedge member has an upstanding flange 72 through which 10 passes an adjusting bolt 73 threaded into the carrier frame and by turning of which the lengthwise position of the corresponding wedge block may be adjusted. The bars 62 and 63 may be held to their respective frames 15 by means of bolts 74 (see Figure 1) which may be slackened up or tightened in accordance with the adjustment which it is desired to make by movement of the wedge blocks.

Provision is also made by which the carrier belts are driven by power by a mechanism entirely separate from the power mechanism for raising and lowering the upper carrier and the antifriction plate. This independent actuation is desirable since if both were 20 driven from the same mechanism should the travel of the belts stop with the skin in position therebetween, the power mechanism for separating the carriers would also fail, and it would be difficult to remove the skin 25 since it would be necessary to raise the upper carrier by hand against its unbalanced weight. It is also desirable to insert the skin while the belts are running, the engagement of the running belts with the skin serving to position 30 it within the machine properly for the subsequent operation after the carriers have been brought together. For this reason, therefore, the shaft 22 has been provided which carries outwardly of the end frame 35 through which it passes tight and loose driving pulleys 80 and 81 over which a drive belt from any suitable source of power may engage, the position of this belt on the pulleys being controlled by a belt shipper comprising 40 a shipper yoke 82 carried at the upper end of a lever 83 pivoted at 84 to a bracket 85 extending outwardly from the end frame. To the lower end of this lever is pivoted 45 a link 86 pivotally connected to an arm 87 fixed to a rock shaft 88 which may be rocked by a handle 89 adjacent this end of the machine. The shaft 22 has fixed thereto a driving gear 90 with which meshes a gear 91 fixed to the rear driving shaft 92 of the lower carrier, this shaft carrying the rear roller for 50 the belt as in the machine of the above mentioned patent. This gear 91 meshes with an idler 93 which in turn meshes with a gear 94 fixed to the shaft 4. Shaft 21 carries similar 55 tight and loose pulleys 97 and 98 and a belt shipper mechanism similar to that described in connection with the pulleys 80 and 81 and controlled by a handle 99 similar to the handle 89 but adjacent the other end of 60 the machine is employed.

The clutch above mentioned for controlling the motion of the eccentrics 29 on rotation of the shaft 28 as shown is of a type which permits one half a revolution of the shaft 28 at each actuation, it being so designed that when pressure is applied to a treadle, here indicated at 100, the upper bolster or carrier being in raised position, one half a rotation is imparted to the shaft 28 and the upper carrier and friction plate are allowed to descend into working position. On removing the foot from the treadle 100 the shaft 28 is again coupled for rotation for the other half of its revolution, whereupon the upper carrier and the antifriction plate are raised to 70 their inoperative positions. Details of the clutch capable of this operation are shown in Figures 5 to 10.

Referring to these figures it will be noted that the gear 27, which is mounted for rotation relative to the shaft 28, is recessed in one end face as at 105. Within this recessed portion are set fixed clutch elements comprising a series of pins 106, each, as shown, having a flattened face 107 for engagement with a movable clutch element in the driven member. This movable clutch element comprises a pin 108 slidable axially in a socket recess 109 in a collar 110 keyed to the shaft 28. The recess 109 is provided with a slot 111 extending outwardly through the adjacent peripheral portion of the collar and within this slot rides a boss 112 projecting laterally from the pin 108. This boss has fixed therein the inner end of a journal pin 113 on which 85 is journaled a roller 114. It is evident that when the pin 108 is projected to extend within the path of motion of the pins 106 the driven member comprising the collar 110 is 90 coupled for rotation with the driving member comprising the gear 27, and that when the pin 108 is retracted within its socket out of the path of motion of the pin 106, the driven member is disconnected from the driving member and the rotation of the driving 95 shaft may stop. Provision is made by which the pin 108 is resiliently urged into clutching engagement. In clutches of this general type difficulty is often experienced due to improper retraction of the projecting pin so 100 that it does not entirely clear the fixed clutch elements and is thus caused to impinge thereon, causing chipping of certain of the parts 105 as well as a noisy operation and uncertainty in operation. To overcome this difficulty 110 means have been provided in this machine by which when the clutch is in unclutched relation the pressure exerted by the spring on the movable clutch element is entirely removed. For this purpose a pin 115 is positioned within the recess 109 so as to bear 115 against the rear end of the pin 108, this pin 115 being acted upon by a spring 116 seated in the recess and as shown reacting against the rear wall of the recess and the forward 120 125 130

wall of a recess 117 within the pin 115, this latter recess being provided to permit the use of a relatively long spring and pin 115 without requiring an excessive length of the collar 110. This pin 115 is also provided with a boss 118 riding in the slot 111, this boss carrying journaled on a pin 119 fixed thereto a roller 120. It will be noted that this roller 120 is of less length than the roller 114, this being for a purpose which will later appear.

Referring more particularly to Figures 5 and 6, a member for controlling the projection and retraction of the pins 108 and 115 is shown. This member comprises an upper arcuate cam portion 125 and a lower similar portion 126 which are fixed together in spaced relation by means of a pair of studs 127 extending therethrough adjacent opposite ends, these studs being slidable through fixed bearing bosses 128 and 129 which are shorter than the space between the sections 125 and 126 so as to permit these sections to move upwardly and downwardly a limited amount. Each of the upper and lower portions 125 and 126 carry a pair of inclined cam faces 130 and 131, the upper cam face 130 being so positioned that when the control member is in depressed position, the roller 120, as the collar 110 rotates, is engaged thereby and retracted against the tension of the spring 116 out of contact with the rear end of the pin 108. As soon as this has been moved out of contact, however, the roller 114 is engaged by the cam face 131 so that the pin 108 is retracted from clutching engagement with its cooperating fixed pin of the driving element, whereupon the collar 110 is disconnected from the driving member and the rotation of the shaft ceases. If now the control member be raised upwardly to its opposite limit of motion, the cam elements 130 and 131 are raised, the upper cam element 130 first releasing the roller 120 since this is shorter than the roller 114 and then the roller 114 being released from the upper element 131. The releasing of the roller 120 permits the spring 116 to project the pin 115 against the rear end of the pin 108 and a subsequent release of the roller 114 permits the spring 116 acting through the pin 115 to project the pin 108 into clutching engagement with one of the fixed pins 106 of the driving member whereupon the shaft 28 is uncoupled for rotation. This raising of the control member, however, brings the cam inclines 130 and 131 on the lower portion 126 into such positions that when the shaft 28 substantially completes one half a revolution the pin 115 and then the pin 108 have been retracted in the same manner that they were retracted by the cam faces of the upper portion, thus disconnecting the driven from the drive member. If the control member be then depressed the pin 115 and then the pin 108

are released, permitting the spring 116 to force the pin 108 into clutching position to couple the drive and driven member for the next half of the rotation, whereupon they are disconnected again by the action of the cam faces on the upper portion 125 of the control member. This control member is moved from one to the other of its positions by means of the treadle 100, the lower portion 126 having a depending perforated ear 135 for attachment to a link 136 fixed to the treadle, a spring 137 acting to raise the control member when pressure is removed from the treadle. As shown the bearing members 128 and 129 through which the studs 127 are slidable are at the ends of a yoke frame 140 which has a central arcuate web portion 141 made fast to the cross frame member 24 of the machine, as by bolts passing through slotted openings 142 therein. As shown also this yoke frame has a perforated ear 143 projecting therefrom to which the upper end of the spring 137 may be attached.

In order to avoid overrunning of the shaft 28 after it has been unclutched from the gear 27 it is desirable to apply some resistance to the turning of the shaft. This is preferably accomplished by means of a brake comprising a brake drum indicated at 150 which is fixed to the shaft 28 and over which bears a friction element 151 having a resilient forwardly projecting arm 153 which may be drawn downwardly against the drum by means of a bolt and thumb nut 152 mounted on the frame of the machine. The friction produced by this device is sufficient to stop the shaft 28 when the clutch is disconnected, but is of such a small amount as to impart no appreciable resistance or consumption of excess power in the operation of the machine. The clutch mechanism is so arranged that when the treadle is in elevated position, the upper carrier and the antifriction plate are also elevated and when pressure is applied to the treadle the antifriction plate and the upper carrier are both brought down into operative position and are so held as long as the treadle is held depressed. As soon as the treadle is allowed to rise, the shaft 28 rotates a further half revolution and elevates the upper carrier and the plate 40.

The subject matter of the clutch mechanism is described and claimed in my application for Patent Serial No. 727,105 for clutches filed July 1, 1924, as a division from the present application.

Having thus described an embodiment of this invention it should be evident to those skilled in the art that many changes and modifications may be made therein without departing from its spirit or scope as defined by the appended claims.

I claim:

1. A machine of the class described comprising a pair of endless belt carriers having

stretches in confronting relation, a plate positioned between said stretches, and power means for positively separating said stretches and spacing said plate therefrom to permit the insertion of work and for permitting said stretches and plate to approach each other to engage the work.

2. A machine of the class described, comprising a pair of endless belt carriers having stretches in confronting relation, a plate positioned between said stretches, means for positively separating said stretches and spacing said plate therefrom to permit the insertion of work and for permitting said stretches and plate to approach each other to engage the work, and power means for driving said carriers.

3. A machine of the class described, comprising a pair of endless belt carriers having stretches in confronting relation, a plate positioned between said stretches, power means for positively separating said stretches and spacing said plates therefrom to permit the insertion of work and for permitting said stretches and plate to approach each other to engage the work, and power means for driving said carriers.

4. A machine of the class described, comprising a pair of endless belt carriers having stretches in confronting relation, one of said carriers comprising a system of rolls in fixed position, the other said carrier comprising a system of rolls rockable about the axis of one of the rolls, and power means for rock-
35 ing said rockable system away from the fixed system and for permitting the rockable system to rock toward the fixed system under gravity.

5. A machine of the class described, comprising a pair of movable surface members arranged in confronting relation, a normally stationary member between said movable surface members, means for controlling the spacing of said members, power mechanism for actuating said means, and other power mechanism for moving said movable surface members.

6. A machine of the class described, comprising a pair of superposed movable surface members, power means controllable to raise the upper member to permit work to be inserted between said members and to permit said upper member to descend by gravity to engage the work between said members, and means for moving said surface members.

7. A machine of the class described, comprising a pair of superposed movable surface members, a normally stationary member between said movable surface members, power means controllable to raise the upper movable surface member from said normally stationary member and said normally stationary member from said lower movable member to permit the insertion of work and to permit said normally stationary member and said

upper movable member to descend by gravity to engage the work.

8. A machine of the class described comprising upper and lower endless surface carriers, the upper of said carriers being arranged to tilt toward and from the lower carrier, a pair of shafts arranged below said carriers, connections from one of said shafts for driving said carriers, a third shaft, connections from the other of said pair of shafts to said third shaft including a half revolution clutch, mechanism actuated from said third shaft for tilting said upper carrier away from said lower carrier during one half the revolution of said third shaft and for permitting said upper carrier to tilt toward said lower carrier during the other half of the revolution of said third shaft, and separate power mechanism for driving each of said pair of shafts.

9. A machine of the class described comprising upper and lower endless surface carriers, the upper of said carriers being arranged to tilt toward and from the lower carrier, a plate positioned between said carriers, a pair of shafts arranged below said carriers, connections from one of said shafts for driving said carriers, a third shaft, connections from the other of said pair of shafts to said third shaft including a half revolution clutch, mechanism actuated from said third shaft for tilting said upper carrier away from said lower carrier and raising said plate from said lower carrier during one half a revolution of said third shaft and for permitting said plate to lower and said upper carrier to tilt toward said lower carrier during the other half of the revolution of said third shaft, and separate power mechanisms for driving said pair of shafts.

10. In a machine of the class described, a pair of superposed endless belt carriers, the upper of said carriers being pivoted to rock downwardly toward said lower carrier and upwardly away therefrom, a shaft below said lower carrier, eccentrics on said shaft, straps for said eccentrics, rods fixed to said straps and slidably engageable with said upper carrier at one side of its pivot, an abutment on each rod beneath said carrier for impinging thereon and raising said carrier as said rods raise, and means for rotating said shaft by increments of one half a revolution to maintain said upper carrier in either its raised or lowered position when said shaft is stopped.

11. In a machine of the class described, a pair of superposed endless belt carriers, the upper of said carriers being pivoted to rock downwardly toward said lower carrier and upwardly therefrom, a plate between said carriers, a shaft below said lower carrier, eccentrics on said shaft, straps for said eccentrics, rods fixed to said straps and slidably engaging said upper carrier at one side of

its pivot, an abutment on each rod beneath said carrier for impinging thereon and raising said carrier as said rods raise, levers each having its free end operatively connected to said plate and engaged intermediately by one of said eccentrics to raise said plate from said lower carrier when said upper carrier is raised but to a less extent, and to permit said plate to move downwardly toward said lower carrier as said upper carrier rocks downwardly, and means for rotating said shaft by increments of one half a revolution to maintain said upper carrier and plate in either raised or lowered position when said shaft is stopped.

12. In a machine of the class described, a bolster comprising a pair of spaced parallel rollers, an endless belt passing over said roller, a support for one stretch of said belt between said rollers comprising a bar positioned transversely thereof, and means comprising endwise movable wedges for adjusting the position of said bar substantially perpendicular to said stretch.

13. In a machine of the class described, a bolster comprising a frame, a pair of spaced parallel rollers journaled in said frame, an endless belt passing over said rollers, a support for one stretch of said belt between said rollers comprising a bar positioned transversely thereof and made fast to said frame, said bar having its ends tapered, and a wedge engaging each of said tapered ends and adjustably fixed to said frame, the adjustment of said wedges adjusting said bar substantially perpendicular to said stretch.

14. In a machine of the class described, a pair of superposed endless belt carriers, a plate intermediate said carriers having a bead along one edge, and means acting at the opposite edge for counterbalancing the weight of said bead.

15. In a machine of the class described, a plate having a bead along one edge, yokes for supporting said plate, each yoke having a perforation therethrough, a rod through each perforation carrying a member engaging the yoke to raise said plate as said rods are raised and to permit said plate to fall as said rods descend, raising and lowering members to which the lower ends of said rods are attached, and springs reacting between the edge of said plate opposite to said bead and said members for counterbalancing said bead.

16. In a machine of the class described, a plate having a bead along one edge, yokes for supporting said plate, a rod adjustably fixed to each yoke for raising said plate as said rods are raised and to permit said plate to fall as said rods descend, raising and lowering members to which the lower ends of said rods are attached, springs reacting between the edge of said plate opposite to said bead and said members for counterbalancing said bead,

and means for adjusting the tension of said springs.

17. In a machine of the class described, a pair of superposed endless belt carriers, a plate positioned between said carriers, and on which work to be treated between said carriers is placed, and means for counterbalancing the weight of the work on the forward portion of said plate.

18. In a machine of the class described, a plate having a bead along one edge, a pair of rods for supporting said plate, a guide through which each rod slides to raise and lower said plate, means for sliding said rods, and springs reacting between the edge of said plate opposite to said bead and said sliding means to prevent cramping of said rods in said guide.

In testimony whereof I have affixed my signature.

JOHN E. SPENCER.
